[57] CLAIM

The ornamental design for a combined hood and ignition lock, as shown.

DESCRIPTION

FIG. 1 is a side elevational view of a combined hood and ignition lock showing my new design;

FIG. 2 is an enlarged fragmentary side elevational view thereof showing the lock mechanism and lock chamber portion;

FIG. 3 is a top plan view of FIG. 2;

FIG. 4 is a bottom plan view of FIG. 2;

FIG. 5 is a front elevational view of FIG. 2;

FIG. 6 is a sectional view taken along lines 6—6 in FIG. 2 showing the lock chamber portion with the lock mechanism removed; and

FIG. 7 is an enlarged rear elevational view of FIG. 1.
